OLIVER C. THOMPSON, OF PHOENIX, ARIZONA.

COMPOUND RAIL.

1,171,278.

Specification of Letters Patent.

Patented Feb. 8, 1916.

Application filed April 30, 1915. Serial No. 24,865.

To all whom it may concern:

Be it known that I, OLIVER C. THOMPSON, a citizen of the United States, residing at Phoenix, in the county of Maricopa and 5 State of Arizona, have invented certain new and useful Improvements in Compound Rails, of which the following is a specification.

This invention relates to railroad rails 10 and more particularly to compound rails.

One of the principal objects of the invention is to provide an improved compound rail adapted to be easily assembled and disassembled for renewal of worn parts, and 15 adapted to be maintained in locked position by action of the car wheels passing over the rail.

A further object of the invention is to provide a compound rail including a resilient 20 filler upon which a tread portion in the form of a cap or facing plate is locked, said cap or facing adapted to be removed when worn.

Another object of the invention is to provide an improved compound rail which will 25 be extremely simple, durable, efficient in operation and inexpensive to manufacture.

With these and other objects in view which will become apparent as the description 30 proceeds, the invention resides in the construction, combination and arrangement of parts, hereinafter more fully described and claimed, and illustrated in the accompanying drawing, in which like characters 35 of reference indicate like parts throughout the several figures, of which—

Figure 1 represents a view in side elevation of a rail constructed according to my invention, parts being broken away to expose the interior structure thereof. Fig. 2 40 represents a top plan view of a rail constructed according to my invention. Fig. 3 represents a vertical transverse sectional view taken on the plane indicated by the 45 line 3—3 of Fig. 1. Fig. 4 represents a fragmentary perspective view of adjacent ends of locking bar sections showing the construction of the same. Fig. 5 represents a fragmentary vertical sectional view, showing 50 one of the locking bars as equipped with an eye bolt.

In carrying out my invention I provide a roadbed or trackway indicated generally at 5 and formed of concrete or other composite 55 or monolithic material. The adaptation of the rail for use with such a road-bed renders

the former of particular use in paved streets, although it will be understood an independent base or trackway may be constructed. The base or road-bed is channeled as at 6 for the reception of the trough 7. The latter includes a floor 8 disposed horizontally, a vertical outer wall 9 whose upper portion 10 is off-set inwardly from the lower portion thereof so that a shoulder 60 11 is formed at any desired height on the outer wall, and an inner wall 12. The latter is disposed at a slight angle and bears away from the outer wall. The side walls 9 and 12 are provided with outwardly extending 70 horizontal flanges 13 and 14 respectively, whose upper surfaces lie flush with the upper surfaces of the road-bed 5. Flange 14 is connected with wall 12 by means of a curved portion 15 which presents a concaved surface on the inner side of the wall, thus forming a groove or flangeway suitable 75 to receive the flange of an ordinary car wheel. Stamped from the flanges 13 and 14 either at the ends thereof or intermediate 80 their ends or both, are the depending substantially vertical anchor bars or strips 16. The latter depend alongside and in spaced relation to the walls of the trough and are embedded in the road-bed for anchoring the 85 trough rigidly thereto.

Adapted to be disposed within the trough is a wooden or other resilient filler 17 crowned with a facing or tread plate 18. Filler 17 as indicated may be made of wood 90 or wood pulp, papier mâché, or other suitable material characterized by a certain amount of compressibility or resiliency. The bottom face of the filler rests flat against floor 8 of the trough, and is of a 95 width somewhat less than the distance between walls 9 and 12 at the lower portion of the latter. The sides of the filler are substantially vertical, the upper portion of said filler being reduced so that 100 the crown or tread plate 18 may be disposed thereupon. Said plate has a tread portion 19 conforming to that of any approved rail section depending from which and at right angles thereto are side flanges 105 20 and 21. The outer face of the former lies flush with the adjacent face 22 of the filler. The lower edge of depending flange 21 is flared outwardly at 23 and rests in a concaved surface 24 provided in the outer 110 face of filler 17. The flared portion 23 is adapted to be locked into position with

shoulder 11 by means of a wedge bar 25, to prevent vertical movement of the filler and crown plate relative to the trough.

The wedge bar 25 is provided with a vertical face 26 adapted to lie flat against the outer face of depending flange 20 and the adjacent face 22 of the filler. The opposite edge or face of the wedge bar is inclined, so that when the bar is dropped between the filler and wall 12 of the trough, there may be a wedge action between wall 12 and the wedge bar, whereby the filler together with its crown plate are wedged against the opposite wall 9 of the trough and locked in fixed position with said trough by reason of the shoulder 11 and flared flange 23. When the parts are in this position a slight space indicated at 27 is left between the lower edge of the wedge bar and the floor 8 of the trough, so that if the filler and the crown plate should wear on their lateral faces the bar may gradually work downwardly so as to always maintain said filler and crown plate in locked and immovable position.

It will be noted that the upper edge of lock bar 25 occurs adjacent the lower edge of curved portion 15 of the inner wall of the trough, so that the car wheels in rolling over the rail may contact with said lock bar for maintaining the same in position. The relative position of the car wheel with the rail is indicated in dotted lines in Fig. 3.

The trough, filler, crown plate and lock bar are made in sections which are assembled end to end in constructing a track, but the joints thus formed in the separate pieces do not occur at the same places, but are placed at various intervals to each other. For instance, in Fig. 2 the transverse dotted line 28 indicates the joint between two filler sections, the transverse line 29 indicates the joint between two crown plate sections, and the transverse line 30 indicates a joint between two wedge bar sections. The ends of the wedge bar sections are as indicated in Fig. 4 provided with interlocking lugs and recesses 31 and 32 respectively, of a shape similar to that indicated, or of some other suitable shape, so that separate vertical movement of any single lock bar section after the track rail is assembled is thus prevented.

When any crown plate becomes worn and is to be renewed, the adjacent wedge bar sections may be lifted, and the old plate removed and a new one put into place upon the old filler, whereupon the bars will be dropped back into position. The arrangement provides for the expansion and contraction of the various metallic parts due to the changes in temperature, since the wooden or resilient fillers will accommodate slight changes in dimensions of the

metallic parts due to either expansion or contraction. No fastenings which are often times expensive to manufacture and require careful and frequent watching are used with my rail, the only adjustable part being the wedge bar, which as before stated is maintained in place mainly by the action of the passing wheels.

In order that the wedge or lock bars may be raised when necessary, each of them is provided adjacent one end with a threaded opening or socket 33, normally occupied by a threaded plug 34. The plug is provided with a groove in its upper end whereby it may be engaged by a screw driver or similar instrument for removal. When it is desired to remove a section of the bars the desired plugs may be taken out and eye bolts 35, as shown in Fig. 5, may be substituted for them, thus affording a medium whereby any suitable lifting force may be transferred to the bars.

Although I have described the preferred embodiment of my invention, I may desire to make such changes in the construction, combination and arrangement of parts thereof as do not depart from the spirit of the invention and the scope of the appended claims.

I claim:—

1. A compound rail comprising a composite road-bed provided with channels therein, a trough disposed in each channel, said trough comprising a horizontal floor, a vertical outer wall, and an inclined inner wall bearing away from the outer wall, said outer wall having its upper portion off-set inwardly whereby a shoulder is provided at a suitable height in said outer wall, outwardly extending flanges provided at the upper edges of the inner and outer walls, said flanges having depending anchors embedded in the road-bed, said inner wall being connected with its horizontal flange by a curved portion exposing a concaved surface toward the outer wall, a filler adapted to be disposed within said trough, and having a reduced upper portion, a crown plate adapted to be disposed upon said filler, said plate including a horizontal tread portion and depending side flanges engaging the sides of the reduced upper portion of the filler, one of said side flanges being provided with an outwardly flared portion adapted to co-act with the shouldered portion of the outer trough wall for preventing vertical movement of the filler and crown plate, and a wedge bar adapted to be disposed between said filler and crown plate, and the inclined wall of the trough, for locking the parts in position.

2. A compound rail comprising a composite road-bed provided with a channel, a trough disposed therein and having an inclined wall, a shoulder formed on the oppo-

including a trough, a
nd provided with a
wedge bar adapted
the crown plate and
the trough for main-
e and filler in posi-
adapted to be main-
ntained in position of passing car
25

including a trough
with an offset por-
ted to be disposed in
adapted to be dis-
een one wall thereof
and a crown plate
il portion and being
between the offset 40
dge bar.

Commissioner of Patents,

site wall of the trough, means for anchoring
said trough to the road-bed, a filler disposed
within the trough, a crown plate carried by
the filler, a wedge bar adapted to be disposed
between the crown plate and filler, and in-
clined trough wall, for forcing said crown
plate and filler against the opposite trough
wall, and means on the crown plate for en-
gaging the said shouldered portion of the
trough wall whereby to prevent vertical
movement of the crown plate and filler.
10
3. A compound rail comprising a com-
posite road-bed having a channel formed
therein, a trough disposed in said channel
and secured to the road-bed, a filler adapted
to be disposed in said trough, a crown plate
removably disposed upon said filler, a wedge
bar adapted to be disposed between the filler
and crown plate and one wall of the trough,
15 and co-acting means between the opposite
wall of the trough and the crown plate for
preventing vertical movement of the crown
plate and filler.
20

4. A compound rail in
filler disposed therein a
removable crown plate, a
to be disposed between the
filler and one wall of the
taining said crown plate
tion, said wedge bar ad-
tained in position by ad-
wheels.

5. A compound rail
having a wall provided
tion, a rail portion adapt-
the trough, a wedge bar
posed in the trough betw
and the rail portion,
